UNITED STATES PATENT OFFICE

ALFRED D. VAN BUREN, OF NEW YORK, N. Y.

DISPENSER

Application filed April 3, 1931. Serial No. 527,533.

The present invention relates generally to a dispenser and more particularly to a device of this character which is for use in ejecting tooth paste, or other semi-fluid substances 5 from collapsible containers or tubes.

An important object of the invention is to provide, in a manner as hereinafter set forth, a dispenser of the aforementioned character embodying a novel construction and arrangement of parts whereby the desired quantity of the paste or cream may be conveniently ejected from the container or tube and whereby the ejecting mechanism may be expeditiously made ready for the reception of a new 10 or full tube and operatively connected or engaged therewith after the contents have been exhausted from one tube or container.

Other objects of the invention are to provide a dispenser of the character described 20 which will be simple in construction, strong, durable, efficient and reliable in use, compact, attractive in appearance and which may be manufactured at low cost.

All of the foregoing and still further objects and advantages of the invention will become apparent from a study of the following specification, taken in connection with the accompanying drawing wherein like characters of reference designate corresponding 30 parts throughout the several views, and wherein:—

Figure 1 is a view in vertical section through a dispenser in accordance with this invention showing, in broken lines, a collapsible tube or container in position therein.

Figure 2 is a view in vertical section taken at right angles to Figure 1 with a tube or container removed.

Figure 3 is a detail view in vertical section 40 through the ejecting mechanism.

Figure 4 is a horizontal sectional view taken substantially on the line 4—4 of Figure 1 looking downwardly and with a tube or container removed.

Figure 5 is a view in end elevation of the 45 ejecting mechanism with the rollers removed.

Figure 6 is a detail view in bottom plan of the rotatable inner cap or closure.

Figure 7 is a detail view in side elevation 50 of the cap or closure illustrated in Figure 6.

Figure 8 is a fragmentary detail view in vertical section and on an enlarged scale showing the means for mounting the ring gear in the cap which is illustrated in Figures 6 and 7.

Referring to the drawing in detail, it will be seen that the reference numeral 1 designates a substantially cylindrical casing of suitable length which is open at its upper end and closed at its lower end, as indicated by the reference numeral 2. The casing 1 has removably mounted therein adjacent diametrically opposite sides thereof a pair of longitudinally extending, spaced, parallel threaded shafts 3 having reduced, unthreaded end portions which are journaled in diametrically opposite sides of the flat rings 4. The rings 4 are slidably insertable in the casing 1 and are provided with notches 5 in outer peripheries for the reception of the inwardly pressed longitudinally extending ribs 6 in upper and lower portions of the casing 1 for retaining the rings against rotation in the casing. Fixed on the end portions of each of the threaded shafts 3 is a pinion gear 7. The shafts 3 are threaded through the end portions of a substantially rectangular metallic plate 8 having an elongated opening therein in which a pair of ejecting rolls 9 are disposed for rotation, said rolls 9 being rotatably mounted on the plate 8.

Pressed outwardly on the upper portion of the casing 1 is a circumferentially extending rib 10. An inner closure or cap 11 is removably and rotatably mounted on the upper end of the casing 1 and has the lower portion of its skirt or flange portion pressed outwardly, as at 12, to provide an internal channel for the reception of the rib 10 for releasably securing the cap 11 on the casing 1 in a manner to permit rotation of said cap thereon. The channelled portion 12 of the skirt or flange of the cap 11 is provided with a series of spaced slits 13 to permit expansion of said portion 12 for engaging the same over the rib 10 or to permit removal of the cap. A ring gear 14 is rigidly secured in an upper portion of the cap 11 and meshes with the pinion gears 7 which are disposed uppermost in the casing 1 when the cap 11 is mounted in

position on said casing. The ring gear 14 may, of course, be secured in position in the cap 11 in any suitable manner. As seen in Figure 8 of the drawing, detents 15 have been 5 pressed from the cap 11 into the ring gear 14 for securing said ring gear in position. The inner cap 11 is provided with a centrally disposed opening 16 for slidably receiving the neck 17 of the collapsible tube or container 18 10 the lower end portion of which is inserted between the rolls 9 when the tube or container is inserted in the device. It will be noted that the neck 17 is not connected with the cap 11. 15 An outer cap or closure 19 of the slip type is removably mounted on the inner rotatable cap 11, the lower or free end of the skirt or flange portion of the outer cap 19 contacting the channelled portion 12 of the inner rotatable cap 11. The top of the outer cap 19 is spaced from the corresponding portion of the cap 11 to accommodate the upstanding neck 17.

In use, the caps 11 and 19 are removed and 20 the tube or container 18 is inserted in the casing 1 through the open upper end thereof, it being understood, of course, that the rolls 9 are disposed in the lower portion of the device. The substantially flat lower end portion of the tube or container 18 is inserted 25 between the rolls 9 after which the inner cap 11 is mounted in position on the casing with the neck 17 of the tube or container projecting through the opening 16. As before 30 stated, the ring gear 14 meshes with the adjacent or upper-most gears 7 when the cap 11 is in position. Now, upon rotation of the cap 11 on the casing 1, the shafts 3 will be 35 rotated in a manner to feed or move the rolls 40 9 upwardly over the tube or container 18, thus squeezing said tube or container between the rolls and ejecting the contents 45 therefrom. It is understood, of course, that the cap 11 is rotated in the correct direction 50 to accomplish this. It will thus be seen that the desired quantity of the contents of the tube 18 may be conveniently ejected therefrom.

To remove and replace the tube from which 55 the contents have been exhausted, the cap 11 is removed and the rings 4 having the shafts 3 and the plate and rolls 9 thereon are withdrawn from the casing 1 through the open upper end thereof and the emptied tube or 60 container is removed after which the unit or mechanism which has thus been withdrawn from the casing is inverted or reversed and reinserted in the casing. It will thus be seen that the rolls 9 will again be disposed 65 in the lower portion of the casing ready to receive a full tube or container. It will also be noted that this has been accomplished without the necessity of rotating the shafts 3 in a reverse direction which, obviously, 70 would require considerable time. When the

device is not in use, the outer cap 19 is mounted in position thereon and protects the projecting neck 17 of the tube or container.

It is believed that the many advantages of a dispenser constructed in accordance with this invention will be readily understood, and although the preferred embodiment of the invention is as illustrated and described, it is to be understood that changes in the details of construction and in the arrangement 75 of parts may be had which will fall within the scope of the invention as claimed.

What is claimed is:—

1. A dispenser for ejecting the contents of a collapsible tube comprising a substantially cylindrical casing, said casing being open at one end and closed at its other end, a pair of spaced rings removably disposed in upper and lower portions of the casing, a pair of threaded shafts disposed in the casing and having their end portions journaled in diametrically opposite sides of the rings, gears fixed on the end portions of the shafts above and below the rings, a pair of opposed rolls 80 rotatably mounted between the shafts for vertical movement on said shafts, the rings and the shafts being reversible in the casing, the rolls being operatively engageable with opposite sides of the tube in a manner to eject the contents thereof, said tube being disposed 85 in the casing, and means for simultaneously rotating the shafts.

2. A dispenser for ejecting the contents of a collapsible tube comprising a substantially cylindrical casing, said casing being open at one end and closed at its other end, a pair of spaced rings removably disposed in upper and lower portions of the casing, a pair of threaded shafts disposed in the casing and having their end portions journaled 100 in diametrically opposite sides of the rings, gears fixed on the end portions of the shafts above and below the rings, a pair of opposed rolls 105 rotatably mounted between the shafts for vertical movement on said shafts, the rings and the shafts being reversible in the casing, the rolls being operatively engageable with opposite sides of the tube in a manner to eject the contents thereof, said tube being disposed 110 in the casing, and means for simultaneously rotating the shafts.

3. A dispenser for ejecting the contents of a collapsible tube comprising a substantially cylindrical casing, said casing being open at one end and closed at its other end, a pair of spaced rings removably disposed in upper and lower portions of the casing, a pair of threaded shafts disposed in the casing and having their end portions journaled in dia- 120

- metrically opposite sides of the rings, gears fixed on the end portions of the shafts above and below the rings, a pair of opposed rolls rotatably mounted between the shafts for 5 vertical movement on said shafts, the rings and the shafts being reversible in the casing, the rolls being operatively engageable with opposite sides of the tube in a manner to eject the contents thereof, said tube being 10 disposed in the casing, means for simultaneously rotating the shafts, said means comprising a removable cap rotatably mounted on the open end portion of the casing, and a ring gear mounted in the cap for rotation 15 therewith and operatively engageable with the adjacent first named gears when the cap is in position on the casing, the rings encircling the tube, the removable cap having a centrally disposed opening therein for the 20 passage of the neck of the tube, and an outer cap removably mounted on the first named cap and enclosing the tube neck.
4. A dispenser comprising a substantially cylindrical container for the reception of a 25 collapsible paste tube, and a reversible unit removably mounted in the casing and operatively engageable with the tube in a manner to eject the contents thereof, said unit comprising a pair of spaced, parallel threaded shafts, rings connecting said shafts together, the shafts having their end portions journaled in diametrically opposite sides of the rings, a plate mounted for longitudinal movement on the shafts, said shafts being 30 threaded through end portions of the plate, said plate having an elongated opening therein, opposed rolls rotatably mounted on the plate and disposed in the opening therein and adapted to receive the tube therebetween, gears fixed on the end portions of the shafts 35 above and below the rings, and means for simultaneously rotating the shafts in a manner to move the rolls over the tube, said means comprising a cap removably and rotatably mounted on the open end portion of the casing, an internal channel in the lower portion of the cap, said channel having a series of spaced, transverse slits therein, a circumferentially extending rib on the casing engageable in the channel in a manner to removably secure the cap in position on the casing, and a ring gear fixed in the cap and operatively engageable with the uppermost 40 of the first named gears for operatively connecting the shafts to the cap for actuation thereby.
6. A dispenser comprising a substantially cylindrical container for the reception of a collapsible paste tube, and a reversible unit 45 removably mounted in the casing and operatively engageable with the tube in a manner to eject the contents thereof, said unit comprising a pair of spaced, parallel threaded shafts, rings connecting said shafts together, the shafts having their end portions journaled in diametrically opposite sides of the rings, a plate mounted for longitudinal movement on the shafts, said shafts being 50 threaded through end portions of the plate, said plate having an elongated opening therein, opposed rolls rotatably mounted on the plate and disposed in the opening therein and adapted to receive the tube therebetween, gears fixed on the end portions of the shafts 55 above and below the rings, and means for simultaneously rotating the shafts in a manner to move the rolls over the tube.
5. A dispenser comprising a substantially cylindrical container for the reception of a collapsible paste tube, and a reversible unit 60 removably mounted in the casing and operatively engageable with the tube in a manner to eject the contents thereof, said unit comprising a pair of spaced, parallel threaded shafts, rings connecting said shafts together, the shafts having their end portions journaled in diametrically opposite sides of the rings, a plate mounted for longitudinal movement on the shafts, said shafts being 65 threaded through end portions of the plate, said plate having an elongated opening therein, opposed rolls rotatably mounted on the plate and disposed in the opening therein and adapted to receive the tube therebetween, gears fixed on the end portions of the shafts 70 above and below the rings, and means for simultaneously rotating the shafts in a manner to move the rolls over the tube, said means comprising a cap removably and rotatably mounted on the open end portion of the casing, an internal channel in the lower portion of the cap, said channel having a series of spaced, transverse slits therein, a circumferentially extending rib on the casing engageable in the channel in a manner to removably secure the cap in position on the casing, and a ring gear fixed in the cap and operatively engageable with the uppermost 75 of the first named gears for operatively connecting the shafts to the cap for actuation thereby.
6. A dispenser comprising a substantially cylindrical container for the reception of a collapsible paste tube, and a reversible unit 80 removably mounted in the casing and operatively engageable with the tube in a manner to eject the contents thereof, said unit comprising a pair of spaced, parallel threaded shafts, rings connecting said shafts together, the shafts having their end portions journaled in diametrically opposite sides of the rings, a plate mounted for longitudinal movement on the shafts, said shafts being 85 threaded through end portions of the plate, said plate having an elongated opening therein, opposed rolls rotatably mounted on the plate and disposed in the opening therein and adapted to receive the tube therebetween, gears fixed on the end portions of the shafts 90 above and below the rings, and means for simultaneously rotating the shafts in a manner to move the rolls over the tube, said means comprising a cap removably and rotatably mounted on the open end portion of the casing, an internal channel in the lower portion of the cap, said channel having a series of spaced, transverse slits therein, a circumferentially extending rib on the casing engageable in the channel in a manner to removably secure the cap in position on the casing, and a ring gear fixed in the cap and operatively engageable with the uppermost 95 of the first named gears for operatively connecting the shafts to the cap for actuation thereby.
6. A dispenser comprising a substantially cylindrical container for the reception of a collapsible paste tube, and a reversible unit 100 removably mounted in the casing and operatively engageable with the tube in a manner to eject the contents thereof, said unit comprising a pair of spaced, parallel threaded shafts, rings connecting said shafts together, the shafts having their end portions journaled in diametrically opposite sides of the rings, a plate mounted for longitudinal movement on the shafts, said shafts being 105 threaded through end portions of the plate, said plate having an elongated opening therein, opposed rolls rotatably mounted on the plate and disposed in the opening therein and adapted to receive the tube therebetween, gears fixed on the end portions of the shafts 110 above and below the rings, and means for simultaneously rotating the shafts in a manner to move the rolls over the tube, said means comprising a cap removably and rotatably mounted on the open end portion of the casing, an internal channel in the lower portion of the cap, said channel having a series of spaced, transverse slits therein, a circumferentially extending rib on the casing engageable in the channel in a manner to removably secure the cap in position on the casing, and a ring gear fixed in the cap and operatively engageable with the uppermost 115 of the first named gears for operatively connecting the shafts to the cap for actuation thereby.
- In testimony whereof I affix my signature.
- ALFRED D. VAN BUREN.
